(57) **CLAIM**

What is claimed is the ornamental design for a hair dryer holder, as shown and described.

DESCRIPTION

FIG. 1 is a perspective view of a hair dryer holder showing a new design;

FIG. 2 is a top view of the hair dryer holder of FIG. 1;

FIG. 3 is a cross-sectional view taken along line 3-3 of FIG. 2;

FIG. 4 is a front view of the hair dryer holder of FIG. 1;

FIG. 5 is a bottom view of the hair dryer holder of FIG. 1;

FIG. 6 is a rear view of the hair dryer holder of FIG. 1;

FIG. 7 is a right side view of the hair dryer holder of FIG. 1;

FIG. 8 is a left side view of the hair dryer holder of FIG. 1;

FIG. 9 is a perspective view another embodiment of the hair dryer holder of FIG. 1; and,

FIG. 10 is a cross-sectional view along line 10-10 of FIG. 9. The components of the display shown in broken lines illustrate portions of the hair dryer holder form no part of the claimed design.

1 Claim, 4 Drawing Sheets
